United States Patent Office.

LUDWIG IGNATIUS TRUEG, OF ST. VINCENTS, PENNSYLVANIA.

Letters Patent No. 98,320, dated December 28, 1869.

IMPROVEMENT IN SUN-DIALS.

The Schedule referred to in these Letters Patent and making part of the same.

To all whom it may concern:

Be it known that I, LUDWIG IGNATIUS TRUEG, O. S. B., of St. Vincents, in the county of Westmoreland, and State of Pennsylvania, have invented a new and improved Sun-Dial; and I do hereby declare that the following is a full, clear, and exact description thereof, which will enable others skilled in the art to make and use the same, reference being had to the accompanying drawing, forming part of this specification, in which—

Figure 1 represents a vertical transverse section of my improved sun-dial.

Figure 2 is a back view of the same.

Figure 3 is a plan or top view of the same.

Similar letters of reference indicate corresponding parts.

This invention relates to sun-dials; and it consists in a novel arrangement and construction of parts, as hereinafter specified.

A, in the drawing, represents a plate or disk, made of wood or other suitable material.

Upon it is pivoted another plate, B, by a vertical pin, *a*.

From the plate B project two vertical posts, C C, to which are secured the ends of a sheet-metal arc, D. The ends of this arc, and the middle of the same, are equidistant from the pivot *a*.

The inner face of the arc is graduated, to indicate the hours and their subdivisions. In line between the pivot and the middle of the arc is fastened, upon the platform A, a vertical plate, E, made in form of a quadrant, and extending, with its front edge, close to the arc.

The plate E projects through a slot of the plate B, to remain stationary with the plate A, while the arc may be turned with B, or *vice versa*.

The ends of the arc have curved slots, through which the pins *b*, that fasten the arc to the posts, are fitted. The arc can thus be not only swung on its pivots *b*, but can also be so set thereon that its inner face is always parallel with the front edge of E.

A compass, F, is secured upon the plate B, with its centre in line with the pivot *a* and plate E.

The device is used in the following manner:

It is set up, with the plate E in line with the needle of the compass, and with the middle of the arc also in line with the same. The arc is then set at a degree corresponding to the degree of latitude in which the device is set up.

To facilitate this adjustment, figures may be marked near the slots at the ends of the arc. The shadow of the plate E falling upon the arc, will denote thereon the correct time. But as the clock time varies more or less from the true time shown by the sun, the arc may be shifted sideways on the pivot *a*, to let the shadow indicate the regular clock time.

The plate E is made so much larger than a quadrant as to add, with the thus enlarged shadow, the time apparently lost by our inability to perceive the sun in the exact position which it occupies.

Having thus described my invention,

I claim as new, and desire to secure by Letters Patent—

The graduated arc D, provided with slotted ends, in combination with the quadrant or gnomon E, and pivoted plate B, as shown and described.

LUDWIG IGNATIUS TRUEG, O. S. B.
